UNITED STATES PATENT OFFICE

157,942

OPERATOR'S CAB FOR CRANES

Ernst L. Collin, Rockford, Ill., assignor to Harnischfeger Corporation, Milwaukee, Wis., a corporation of Wisconsin

Application March 1, 1948, Serial No. 144,851

Term of patent 14 years

(Cl. D14—3)

To all whom it may concern:

Be it known that I, Ernst L. Collin, a citizen of the United States of America and residing at Rockford, in the county of Winnebago and State of Illinois, have invented a new, original, and ornamental Design for an Operator's Cab for Cranes, of which the following is a specification, reference being had to the accompanying drawings, forming a part thereof.

In the drawings,

Fig. 1 is a perspective view of an operator's cab for cranes, showing my new design,

Fig. 2 is a plan view of my new design,

Fig. 3 is a side elevational view of my new design,

Fig. 4 is a front elevational view of my new design, and

Fig. 5 is a side elevational view of my new design showing the upper part in an open position, parts of the lower part being broken away.

The characteristic features of my design reside in the portions shown by means of full lines in the drawing.

I claim:

The ornamental design for an operator's cab for cranes, as shown and described.

ERNST L. COLLIN.
